CLAIM

The ornamental design for a shapewear, as shown and described.

DESCRIPTION

FIG. 1 is a front, left and top perspective view of a shapewear showing my new design;

FIG. 2 is a rear, right and bottom perspective view thereof;

FIG. 3 is a front, left and top perspective view of the shapewear with outerwear and innerwear separated;

FIG. 4 is a rear, right and bottom perspective view of the shapewear with outerwear and innerwear separated;

FIG. 5 a front, left and top perspective view of the outerwear;

FIG. 6 is a rear, right and bottom perspective view of the outerwear;

FIG. 7 is a front view of the outerwear;

FIG. 8 is a rear view of the outerwear;

FIG. 9 is a right view of the outerwear;

FIG. 10 is a left view of the outerwear;

FIG. 11 is a top view of the outerwear;

FIG. 12 is a bottom view of the outerwear;

FIG. 13 a front, left and top perspective view of the innerwear;

FIG. 14 is a rear, right and bottom perspective view of the innerwear;

FIG. 15 is a front view of the innerwear;

FIG. 16 is a rear view of the innerwear;

FIG. 17 is a right view of the innerwear;

FIG. 18 is a left view of the innerwear;

FIG. 19 is a top view of the innerwear; and,

FIG. 20 is a bottom view of the innerwear.

The outerwear and innerwear have been shown separately in FIGS. 3-20 to show aspects of the design that may not be apparent in the other views.

1 Claim, 20 Drawing Sheets
